(57) **CLAIM**

The ornamental design of a automotive wheel lock, as shown and described.

DESCRIPTION

FIG. 1 is a perspective view of an automotive wheel lock according to a first embodiment;

FIG. 2 is a front view of the automotive wheel lock of FIG. 1;

FIG. 3 is a back view of the automotive wheel lock of FIG. 1;

FIG. 4 is a right side view of the automotive wheel lock of FIG. 1;

FIG. 5 is a left side view of the automotive wheel lock of FIG. 1;

FIG. 6 is a top view of the automotive wheel lock of FIG. 1;

FIG. 7 is a bottom view of the automotive wheel lock of FIG. 1;

FIG. 8 is a perspective view of an automotive wheel lock according to a second embodiment;

FIG. 9 is a front view of the automotive wheel lock of FIG. 8;

FIG. 10 is a back view of the automotive wheel lock of FIG. 8;

FIG. 11 is a right side view of the automotive wheel lock of FIG. 8;

FIG. 12 is a left side view of the automotive wheel lock of FIG. 8;

FIG. 13 is a top view of the automotive wheel lock of FIG. 8; and,

FIG. 14 is a bottom view of the automotive wheel lock of FIG. 8.

The structures depicted by way of phantom lines in the drawings are shown for illustrative purposes only and form no part of the claimed design.
